Application December 20, 1940, Serial No. 371,006

15 Claims. (Cl. 45—2)

This invention relates to files for visible indexes and more particularly to improvements in the file disclosed in U. S. Patent No. 1,999,162, patented April 23, 1935.

The present invention comprehends improving on the file shown in the above mentioned patent by providing for a cabinet structure wherein the tray holders may be inserted through the open side of the cabinet; by the provision of retaining means on the open side of the cabinet for detachable mounting on the cabinet to retain the tray holders in assembled relation in the cabinet; by the provision of a cushioning and ejector unit in each tray holder employing a resiliently actuated toggle normally operable to partially eject the card index tray from its compartment and adapted for operation by the card index tray in movement into housed position to over-balance said resiliently actuated toggle for moving and retaining said toggle in straightened position under tension ready to partially eject said tray at the beginning of the next withdrawal movement of the tray from its compartment; the provision of positioning means on the inner or bottom end of each tray holder interengaged with complementary parts on the cabinet for retaining each tray holder in fixed assembled relation in the cabinet; the provision of guide means on the retaining means for the tray holders arranged to not only prevent complete detachment of each card index tray from the cabinet in withdrawn position but also to guide the cover for the cabinet during its movement between open and closed positions, arranged so the cover will completely enclose the retaining means in the closed position to prevent access to both the retaining means, the tray holders and the trays therein; and the provision of cabinet, tray holder, cushioning and ejector units, cover and retaining means arranged for interengaged assembly with one another in relative detachable relation in which all the parts are interengaged in interlocked relation when assembled and the retainer bars retain the various parts in assembled relation to form a plurality of tray compartments in the cabinet to retain card index trays for convenient movement into and out of their respective compartments, at the same time preventing complete detachment from the cabinet.

In the drawings:

Fig. 1 shows the card index file in perspective with the cover in open position and one of the card index trays in a partially projected position obtained by the cushioning and ejector means in the compartment.

Fig. 2 is a vertical longitudinal cross section through the card index file showing the front end of the cover raised slightly above its closed position in full lines and in open position in dot and dash lines, most of the card index trays and the cushioning and ejector units being omitted, and other portions broken away, for convenience in illustrating the invention.

Fig. 3 is a vertical cross section taken on line 10 3—3 of Fig. 2 showing a card index tray in the partially ejected position obtained by the cushioning and ejector means.

Fig. 4 is a cross section taken substantially on line 15 4—4 of Fig. 2.

Fig. 5 is a plan view of the card index file with the cover shown in open position, portions broken away and shown in section to illustrate details of construction and one card index tray shown in a withdrawn position lying on top of the file.

Fig. 6 is a cross section taken on line 20 6—6 of Fig. 4, the scale being enlarged.

Fig. 7 is a cross section taken on line 25 7—7 of Fig. 6 with portions broken away and shown in section for convenience in illustrating details of construction of the cover mounting and guiding mechanism.

Fig. 8 is an enlarged fragmentary detailed cross section showing a cushioning and ejector unit in its assembled relation in a tray holder, the parts being shown in the position for partially ejecting a tray from its tray holder.

Fig. 9 is a cross-section taken on line 30 9—9 of Fig. 8.

Fig. 10 is a bottom plan view of the cushioning and ejector mechanism shown in Fig. 8.

Fig. 11 is a view similar to Fig. 8 showing the cushioning and ejector mechanism at the opposite limit of movement from that shown in Fig. 8, illustrating the position of the parts when the tray is housed in its compartment.

Fig. 12 is a cross-section taken on line 40 12—12 of Fig. 2.

Fig. 13 is a cross-section taken on line 45 13—13 of Fig. 4.

Fig. 14 is an enlarged fragmentary perspective showing the rear end portion of one of the retainer bars.

The card index file forming the present invention is preferably constructed of sheet metal. 50 The cabinet or cabinet body is formed of sheet metal to provide side walls 1 and end walls 2. Side and end walls 1 and 2 are provided with turned flanges at the lower edges indicated at 3 in Figs. 2 to 4. A bottom wall 4 is formed to 55 provide depending marginal flanges that are

adapted to seat on flanges 3 as shown in Figs. 2 and 3 when the bottom wall is inserted through the open upper end of the cabinet into its assembled position.

A pair of angle supporting frames 5 are mounted on the underface of bottom 4 and extend longitudinally along opposite sides thereof to provide a rigid support for carrying the weight of the entire cabinet. Casters may be mounted at opposite ends of angle supporting frames 5 as shown in Figs. 2 and 3 for example, so that the cabinet may be conveniently moved about.

The side and end walls are formed to provide laterally extending flanges forming top wall 6. Top wall 6 is provided with upwardly extending flanges 7 spaced inwardly from the side walls. Upper positioning brackets 8 formed of offset sheet metal strips are mounted at the upper ends of side walls 1 and extend between opposite end walls 2. Positioning brackets 8 are secured in position by spot welding or the like, and define the top opening to the interior of the cabinet for receiving and retaining the tray holders in position. Lower positioning brackets 9 of angular form in cross-section may be used on opposite side edges of bottom 4 as shown in Fig. 3 for example, for receiving the lower ends of the tray holders therebetween and positioning them laterally of base 4.

At the front end of the cabinet, top wall 6 is formed to provide a downwardly and slightly forwardly extending flange having the central portion recessed to receive a key actuated lock 10. A front supporting bracket 11 formed of sheet metal, is mounted at the upper end of front end wall 2 on the inner face thereof so as to extend entirely across the inner face of said end wall to provide a downwardly and rearwardly inclining seat inside the cabinet to define the front end of the tray compartment opening in the cabinet in conjunction with upper positioning brackets 8.

A partition member 12, see Fig. 2, defines the rear end of the space in the cabinet for receiving the tray holders and has the lower end thereof formed to provide a lateral rearwardly extending flange engaged at the rear edge with the inner face of rear end wall 2 at the bottom. Partition 12 inclines upwardly and forwardly from the bottom and terminates at the upper end in a rearwardly extending offset portion 13 formed to provide the front portion of a receptacle seat. The side edges of partition 12 are suitably secured at opposite sides of the upper end to lateral extensions on the front ends of receptacle supporting brackets. A pair of brackets 14 of opposite angular form is mounted on the rear end portions of upper positioning brackets 8. A rear cross bar 15 is secured to lateral extensions on the rear ends of brackets 14 and extends transversely between the rear ends of upper positioning brackets 8 to provide a receptacle seat at the forward edge thereof cooperating with brackets 14 and offset flange structure 13 to provide a complete rectangular seat structure for receiving and supporting card receptacle 16 through the lateral outwardly extending flange around the top thereof.

Card receptacle 16 is suspended from the seat structure in the compartment formed between partition 12 and rear end wall 2 as shown in Fig. 2. A supplemental pin tray or the like 17 may also be suspended in said seat in connection with receptacle 16. The opening to a cover compartment is defined by rear cross bar 15 and the front edge of the depending flange on top wall 6 at the

75 rear end of the cabinet as clearly shown in Fig. 2.

A plurality of tray holders 18 are each individually formed of sheet material and have a plate section 19 formed with a laterally extending back or bottom wall 20. The upper or forward edge of plate section 19 is turned inwardly upon itself as shown in Fig. 2 to eliminate sharp edges. Guide sections are provided at the side edges of plate section 19 extending throughout the length of said plate section. These guide sections are formed by laterally extending flanges 21 on opposite side edges of plate section 19 terminating in flanges 22 extending toward each other in spaced parallel relation to plate section 19. At the inner edges of flanges 22, inturned lip portions 23 extend toward plate section 19 and have the free edges terminating in spaced relation relative thereto to complete the guide sections for guiding the rear end of a card index tray in its sliding movement into and out of said tray holder.

A positioning bar 24 of angular form in cross section has one portion secured by spot welding or the like to the outer face of bottom wall 20, one being applied to the bottom wall of each tray holder. The other portion of positioning bar 24 extends laterally from the free edge of bottom wall 20 and has the free edge thereof provided with a pair of spaced projections 25. Projections 25 engage in a pair of slots formed in bottom wall 4 of the cabinet, for positioning the bottom end of each tray holder against longitudinal and lateral movement relative to bottom wall 4 when the tray holder is interengaged in assembled position in the cabinet as shown in Fig. 2. There are two rows of spaced parallel slots in bottom wall 4, corresponding slots in each row being in transverse alignment to form pairs.

Each tray holder is assembled in the cabinet by inserting it through the open upper end between upper positioning brackets 8 until projections 25 on bar 24 are engaged in a pair of the slots in bottom 4 thereby determining the position of the tray holder in the cabinet. The tray holders in assembled position are preferably arranged in inclined relation as illustrated in Fig. 2, with the lower edge of the tray holder at the bottom end of plate section 19 seated on the upper surface of bottom 4, while the portion of positioning bar 24 carrying projections 25 has its free edge portion arranged at a distance below the free edge of bottom wall 20, a distance so that it will seat on the upper face of bottom 4 to firmly support the bottom of the tray holder on the bottom of the cabinet. Each tray holder has the side opposite plate section 19 open. When a series of tray holders are assembled in adjacent relation in the cabinet as shown in Fig. 2, they cooperate to form tray compartments open only at the upper ends. This is obtained by the plate section 19 of one tray holder closing the open side of an adjacent tray holder.

A cushioning and ejector unit is provided for detachable mounting, one in each tray holder. These units have a bearing plate 26 detachably secured to bottom wall 20 and bar 24 by an attaching screw 27, see Figs. 8 to 11. Screw 27 is the only means of attaching this unit to the tray holder and provides for its ready detachment therefrom when the tray holder is removed from the cabinet. Bearing plate 26 is provided at the side edges with lateral extensions forming spaced parallel bearing projections 28 carrying bearing pin 29 extending between said projections. Positioning projections 30 are formed at the corners

of bearing plate 26 to engage adjacent portions of the tray holder when the bearing plate is mounted on bottom wall 20 for holding the parts of the cushioning and ejector mechanism in a proper aligned position.

A toggle comprising main toggle lever or link 31 and supplemental toggle link 32 is provided in which each of these links is constructed of sheet metal of substantially U-shape in cross section. The side portions of supplemental link 32 are pivotally connected by means of aligned pivot pins 33 to the central portion of the side flanges of main toggle lever 31 on the inner side portions thereof, as clearly shown in Fig. 8. Main toggle lever or link 31 is wider than link 32 in order that the side flanges thereof will embrace link 32 when the toggle is straightened to the position shown in Fig. 11. Pivot brackets 34 are centrally mounted on the inner sides of the side flanges of main toggle lever 31 and cooperate in carrying the pivot pins 33 for providing the toggle pivot connecting lever 31 and link 32. Supplemental toggle link 32 has the opposite end of the side flanges thereon pivotally engaged on bearing pin 29.

The lower end of main toggle lever 31 adjacent bottom flange 20 carries cross pin 35 rotatably mounting a pair of rollers 36 adapted for rolling engagement in the pivotal movement of the toggle levers along the upper inner face of bottom wall 20. Cross pin 35 also forms an anchor for one end of tension coil spring 37, while the opposite end is anchored on bearing pin 29, as illustrated in Fig. 8. This coil spring normally operates to move the toggle into the broken position illustrated in Fig. 8. Main toggle lever 31 has an operating arm 38 carrying cross pin 39 on the free end thereof rotatably mounting fiber roller 40. A cushion pad 41 is riveted on the free end portion of operating arm 38 adjacent roller 40. The purpose of this structure will be described in connection with the operation of this toggle mechanism.

A card index tray 42 is provided for each tray holder. These card index trays are of conventional construction, well known in the art, and include a structure for mounting a plurality of card holders in offset overlapping relation in each tray for hinging movement so that record cards carried by said card holders can be readily inspected and inscribed. The rear end of these trays embodies a slightly different construction than that shown in the aforementioned patent or that used in conventional trays. The rear end of each tray shown in the drawings is provided with an upwardly curved rear end portion 43 formed to provide a tubular portion 44 for receiving axle 45 rotatably carrying supporting rollers 46 on opposite end portions of said tubular portion. The tubular portion 44 terminates in inwardly spaced relation to extensions 47 on the side walls of the card index tray. A reinforcing insert 48 having laterally extending projections 49 at the ends is engaged between the inner faces of said wall projections 47, with the central portion secured to the tray bottom. The end portions of axle 45 pass through apertures in projections 47 and 49 and extend beyond the side walls of the tray as shown in Figs. 3 and 8, to engage in the channels formed by the guide sections on opposite edges of plate member 19 of each tray holder. In this manner, each card index tray is guided in its movement into and out of tray holders 18 while rollers 46 roll on the surface of plate member 19.

A suitable retaining and guide means holds the tray holders assembled in the cabinet against detachment and also retains the card index trays against complete detachment from the cabinet

5 when withdrawn from the tray holders. This is accomplished by employing a pair of guide and retainer bars 50, each oppositely formed of a folded piece of sheet metal to provide inner and outer spaced parallel flange sections 51 and a laterally extending top guide flange section 52. Each retainer bar 50 is mounted along one of the top side edges of the cabinet with spaced flange sections 51 embracing opposite sides of the upwardly extending flanges 7 and the attached upper edge of upper positioning brackets 8, as clearly shown in Figs. 3 and 4.

The retainer bars on opposite sides of the cabinet have the laterally extending guide flanges thereof extended inwardly as shown in Figs. 3 and 4, to extend over the upper open ends of the channels in the guide sections of the tray holders. These flanges are arranged so that upon the withdrawal of a tray from its compartment in a tray holder, axle 45 will have the opposite ends engage guide flanges 52 at opposite sides of the cabinet and prevent complete detachment of the withdrawn tray.

20 A withdrawn tray may then be swung about the axle or rear end into substantially horizontal position and moved back and forth across the other trays in the cabinet with the rollers riding on the upper ends or front walls of the other trays. A withdrawn card index tray while still connected to the cabinet by axle 45 engaging 25 guide flanges 52 may be laid on top of the cabinet for reference to the card holders therein in a manner well known in the art. A plurality of retaining screws are threaded in transverse openings in inner flanges 51, upwardly extending flanges 7 and the upper edges of brackets 8, with the heads preferably at the inner sides of flanges 51.

The inner flange 51 of each retainer bar 50 is provided throughout that portion of its length 30 overlying the ends of tray holders 18 with bifurcated positioning fingers 53 formed in inwardly offset relation from inner flange 51 in the manner illustrated in Fig. 14. Each of these bifurcated fingers receive the upper edges of the sheet metal forming a pair of adjacent tray holders at the portions of the plate sections 19 and flanges 22 in contact with each other.

35 These retainer bars 50 extend rearwardly beyond partition 12 and have their rear ends projecting into the cover receiving opening where inwardly offset extensions 54 carry guide pins 55. These guide pins project inwardly toward each other. Tray stops 56 and 57 are provided at the front and rear portions of retainer bars 50 as shown in Figs. 1, 2 and 14, for limiting the travel of the card index trays along the top of the file while being guided by said retainer bars.

40 A sheet metal cover 58 is adapted to extend over the entire top of the cabinet in the closed position. It is provided with depending marginal flanges arranged when the cover is in closed position on top of retainer bars 50 to extend downwardly outside of the front, side and rear ends of the retainer bars into a position adjacent the upper surface of top wall 6 for entirely enclosing and preventing access to the retainer bars, the trays, or any part of the interior of the cabinet.

45 Guide bars 59 are mounted on the inner face of 75 cover 58 at opposite sides thereof as clearly

shown in Fig. 7, in order to provide outwardly facing guide channels for receiving guide pins 55.

The rear end of the cover is provided with a hinge connection at 60 as shown in Fig. 4 with a follower 61. Follower 61 is detachably connected by screws 62 to a guide member having offset side edge portions slidably engaged in guide channel 64 secured to the central portion of rear end wall 2 in vertically extending relation, as shown in Figs. 4 and 13. A rubber or similar composition bumper block 65 is mounted in the lower end of channel 64 as shown in Figs. 2 and 4 to provide a noiseless shock absorbing stop for limiting the downward movement of the cover at the bottom of its movement into open position in the rear portion of the cabinet. This is obtained by a lateral projection on follower 61 extending into the channel 64 and engaging the upper end of resilient bumper block 65.

The follower is limited in its upward movement in channel 64 by engaging the under face of top wall 6. The cover is also provided with a keeper for cooperation with lock 10 on the front of the cabinet when the cover is locked in closed position. The follower on the rear end of the cover will prevent the cover from being lifted up from the top of the cabinet. A handle 66 is mounted in a convenient manner on the front end of the cover for use in convenient manual operation of the cover between its open and closed positions.

A suitable correspondence or paper holder is provided in attached relation on the cover in order to hold the loose cards, papers, etc., in a convenient position for manual manipulation while the records carried by this cabinet are being worked upon by an operator. The correspondence holder has a supporting plate 71 provided with reversely bent spaced side portions to provide guide members to embrace the free inner edges of guide bars 59 to slidably mount the holder on the cover. The lower end of plate 71 is provided with a lateral forwardly extending tubular section 78 providing a pivotal support for flap 79 adapted to close the slot between the lower end of plate 71 and cross bar 15. This flap 79 prevents cards from accidentally sliding through this slot and dropping into the cover compartment.

Plate member 71 is supported by angle brackets 80 mounted on the lower rear face of plate member 71 and arranged in position to engage inwardly extending guide pins 55. These guide pins 55 provide a support for this correspondence holder, while the cover can be slidably moved into open and closed positions during which time the edge portions of the guide bars will slide through the channels formed by reversely bent side portions of plate 71. Supporting plate 71 is provided with a pair of spaced parallel slots 81 extending transversely between the side edges thereof. A pair of holder plates 82 is pivotally mounted on plate 71 in spaced relation each with a portion extending through one of the slots 81. Plates 82 will have limited swinging movement in slots 81. When supported in the inclined position shown in Fig. 6, the rear edges of plates 82 will engage the inner surface of cover 58. These holder plates 82 may be swung into a position where they lie adjacent to plate member 71, the position they occupy when the cover is moved to closed position in the manner shown in Fig. 2, for example. Loose cards, papers, sheets or other similar material may be supported by plates 82 when they are in the angular position shown in Fig. 6 while reference and entries are being

made in the records carried by the card index trays.

This invention provides card index trays, tray holders, cushioning and ejector units and retainer bars made in separate units adapted to be readily positioned and retained in interengaged assembled relation with one another in the cabinet body, solely through the attachment of the retainer bars to the upwardly extending flange portions on the top wall of the cabinet. These retainer bars extend transversely across the upper ends of all of the tray holders and retain the upper ends in the bifurcated projections thereon against longitudinal shifting in the cabinet for effectively retaining the tray holders in assembled relation. The card index trays may be inserted and withdrawn from the compartments; and when withdrawn, the ends of axles 45 will engage guide flanges 52 of retainer bars 50 to retain the trays in attached relation on the cabinet, even in the withdrawn position, for sliding and swinging movement along the top of the cabinet and support in a horizontal position, such as illustrated in Fig. 5, for convenient reference to the records in the tray. The retainer bars also guide cover 58 to prevent its detachment from the cabinet, while the cover cooperates with these retainer bars in the closed position to cover them up and prevent access to any part of the cabinet.

30 A number of advantages are obtained with this construction, one of which is that the tray holders can be assembled in their cooperative compartment forming relation in the cabinet by merely sliding them in through the open top into their 35 interfitted fixed positions wherein they do not require any means of attachment to hold them in position in the cabinet. The retainer bars applied to the top of the cabinet serve as the retaining means for holding these tray holders 40 as well as the trays, in fully operative connection in the cabinet for their normal operation in the use of the records carried in the trays. These retainer bars are readily attachable and detachable from the flanges projecting upwardly from 45 the top wall of the cabinet. This makes the entire structure particularly accessible, due to the fact that upon removal of the retainer bars any tray holder may be removed from the cabinet without removing the others and without 50 having the others becoming disarranged in their assembly in the cabinet.

In the event of difficulty with the operation of any of the cushioning and ejector units, the tray holder containing said unit can be readily 55 removed from the cabinet without disturbing the remaining tray holders and by reason of the tray holder being of open construction, ready access is obtained to the cushioning and ejector unit for either repair, lubrication or replacement. These units are readily replaceable by merely 60 removing the retaining screw and substituting a new unit. The units are constructed for mounting in a fixed position of adjustment with the use of the single screw for mounting the unit in a tray holder. Springs can also be readily replaced in case of breakage. This manner of constructing and assembling the entire file provides for economy in manufacture and the saving of a substantial amount in labor in assembling the 65 parts forming the file as well as in maintenance or repair work.

The guide pins on the retainer bars cooperate with the guide rails on the cover and prevent scraping of the outside of the cover against the 70 back portion of the cabinet as it is moved into

and out of the compartment at the rear of the cabinet and thereby prevents marring of the finish. The cover is made readily detachable from the follower by providing the hinge structure with removable hinge pins that can be detached from the inside of the cover when it is in elevated position extending upward from the rear end of the housing with the follower at its upper limit of movement. This detachment cannot be obtained until the retainer bars are removed from their assembled position on the cabinet, due to the fact, that the channels in the guide bars which receive the guide pins have their ends terminating adjacent to the lateral flanges on opposite ends of the cover in such a manner as to close the ends of these channels.

The entire assembly of the cabinet can be made substantially from the top while the cabinet can be supported on its bottom or on the casters or other support that may be used in lieu thereof.

In operation, a card index tray is removed from the file by manually engaging the handle portion at the front end of the tray indicated at 69, and with a slight upward manual pull assisted by the operation of the cushioning and ejector mechanism, the tray is operated by the cushioning and ejector mechanism to project it partially from the cabinet to the point illustrated by the partially projected tray in Fig. 1. The tray may then be manually gripped and its withdrawal continued in an upward inclined plane directly outward from its compartment until the ends of axle 45 engage guide flange 52 of the retainer bar. When this position is reached the upper end of the tray may be rotated about its rear end after which the rear end of the tray can be moved over the top of the cabinet with rollers 46 supporting the tray for free movement back and forth while the guide flanges of the retainer bars prevent complete detachment of the tray from the cabinet. The tray may be moved into a position on top of the cabinet as shown in Fig. 3 when it will rest in a horizontal position for convenient reference to any card carried by any of the card holders therein through the operation of the index in the usual and well known manner. The tray is replaced in its compartment by reversing the operation above described so that the front end of the tray is raised upwardly as the rear end is moved into a position opposite the open end of its tray holder. Then the tray is aligned with its tray holder so that the rear end will slide downwardly in the tray holder with the axle ends being guided in the guide sections.

As the tray moves downwardly the lower end will engage roller 40 and upon continued downward movement of the tray spring 37 will be stretched against its tension to operate the toggle from the broken position shown in Fig. 8 to the position shown in Fig. 11 wherein the toggle is straightened and the downward movement cushioned to arrest its movement as the tray approaches the bottom of the tray holder. This cushioning action is such that the tray is substantially counter balanced and upon reaching the fully housed position in its tray holder with the bottom of the tray in a position shown in Fig. 11, the motion will be substantially arrested and the operation of the cushioning and ejector unit will be such as to allow the weight of the tray to overcome the tension of the spring by reason of the toggle approaching the dead center position. This provides for the weight of the tray retaining the toggle in the position shown

in Fig. 11 until it is again desired to remove the tray from its compartment. In the event that the tray is shoved downwardly with greater force than necessary to move it to its lowermost position in a tray holder, the side flanges on the main toggle lever will engage bottom wall 20 and the force will then be transmitted through the bottom wall and positioning bar 24 to the bottom of the cabinet where it is distributed. The tray can actually be dropped or allowed to slide of its own weight into its compartment and even be given a shove toward its lower position and the cushioning and ejector mechanism will operate to absorb the shock and gradually stop the movement of the tray toward the bottom of the compartment so that as it reaches the bottom it will remain in housed position.

The paper holder construction carried by the cover can be removed whenever desired by sliding it off of the ends of the guide rails at the front of the cover. When the cover is in open position the plates carried by the paper holder can be positioned as shown in Fig. 1 for convenience in supporting cards, papers and the like used in connection with the records carried in the card index trays so as to facilitate the use of the card index housed in the cabinet. Accessories such as extra cards, card holders, pins, pencils, pens and the like may be kept in the card receptacle and tray at the back of the cabinet for convenient use when the cover is in open position.

The invention claimed is:

1. A card index file, comprising a cabinet having an open top communicating with the open end of an upwardly extending tray compartment therein, a card index tray slidably housed in said compartment in upwardly extending relation, and combined cushioning and ejecting means including a toggle formed of main and supplemental links pivotally connected, means pivotally mounting the free end of one of said links at the bottom of said compartment, the free end of the other link travelling transversely across the bottom of said compartment in the relative pivotal movement of said links and lying substantially straight at the bottom of said compartment with the pivotal connection therebetween adjacent dead center position, said links being retained in said last-mentioned position by the weight of said tray, and an actuating tension spring connecting said links for normally moving said links into broken position to eject said tray partially from said compartment upon withdrawal and to cushion movement of said tray toward housed position therein.

2. A card index file, comprising a cabinet having an open top communicating with the open end of an upwardly extending tray compartment therein, a card index tray slidably housed in said compartment in upwardly extending relation, and combined cushioning and ejecting means including a toggle formed of main and supplemental links, said supplemental link having one end pivotally connected to an intermediate portion of said main link whereby one portion of said main link cooperates with said supplemental link to form a toggle and the other portion forms a toggle actuating arm, means pivotally mounting one free end of said toggle at the bottom of said compartment, a roller on the other free end of said toggle having free rolling movement on the bottom of said compartment, a tension spring connecting the free ends of said toggle normally operative to move said toggle toward broken position for ejecting said

tray partially outward from said compartment, said tray engaging said toggle actuating arm and actuating said toggle against the tension of said spring in movement toward housed position in said compartment for straightening said toggle into a position with the pivot between said links adjacent dead center position where the weight of said tray slightly over-balances said spring and remains in housed position until manually started outward again.

3. A card index file, comprising a cabinet having an open top communicating with the open end of an upwardly extending tray compartment therein, a bottom wall forming the bottom of said tray compartment, a card index tray slidably housed in said compartment in upwardly extending relation, and combined cushioning and ejecting means including a toggle formed of main and supplemental links, said supplemental link having one end pivotally connected to an intermediate portion of said main link, the portion of said main link extending to one side of said pivotal connection with said supplemental link forming the toggle and the portion of said main link at the opposite side of said pivotal connection forming a toggle operating arm, means pivotally connecting the free end of one of said links to said bottom wall in said compartment, anti-friction means on the other free end of said toggle, a tension spring joining the free ends of said toggle for normally actuating said toggle toward broken position with said actuating arm engaging the lower end of said tray in said compartment for projecting said tray partially outward from said compartment, said tray being operable in movement toward housed position in said compartment to engage and actuate said toggle actuating arm for moving said toggle toward straightened position against the tension of said spring to bring the pivot between said links into a position adjacent dead center, and a projection on said main link operable to engage said bottom wall to limit the movement of said toggle as it approaches said straightened position at a point where said tray slightly over-balances the tension of said spring for retaining said tray in housed position in said compartment until manually started outward again.

4. A card index file, comprising a cabinet having an open top communicating with the open end of an upwardly extending tray compartment therein, a card index tray slidably housed in said compartment in upwardly extending relation, a toggle mounted in the bottom of said compartment in transversely extending relation below and engaging the lower end of said tray, resilient means normally operable to move said toggle toward broken position and project the upper end of said tray out of said compartment in the withdrawal of said tray from said compartment, and a pad on said toggle engaged by said tray in movement of said tray toward housed position in said compartment for transmitting the motion of said tray to operate said toggle for straightening said toggle against the tension of said resilient means into the bottom of said compartment with the toggle joint adjacent dead center position wherein the weight of said tray slightly over-balances said resilient means for maintaining said tray in housed position and wherein said pad cooperates to absorb shock and reduce noise in the operation of said tray and toggle.

5. A card index file, comprising a cabinet having an opening at the top, a tray holder detachably mounted in said cabinet through said

open top and arranged in upwardly extending relation, said tray holder having a plate section provided with guides at the sides thereof and a bottom wall at the lower end, said tray holder being open at the upper end and on the side opposite said plate section, a card index tray slideable into and out of the open upper end of said tray holder between said guides at the side edges thereof, and a combined cushioning and ejecting unit detachably mounted on said bottom wall of said tray holder between said guides, for engagement between said bottom wall and the lower end of a card index tray mounted therein, said unit comprising a toggle movable into a straightened position against said bottom wall with the joints of said toggle adjacent dead center position, and resilient means for actuating said toggle toward broken position for engaging the lower end of a tray in said tray holder and projecting it outwardly beyond the top of said cabinet during the withdrawal of said tray from said tray holder, said tray being operable to move said toggle into said straightened position against the tension of said resilient means and being adapted to retain said toggle in said straightened position against said bottom wall through the weight thereof over-balancing the force of said resilient means whereby said tray remains in housed position in said tray holder until manually started outward again, said tray holder being readily detachable from said cabinet to provide access through the open side thereof to said cushioning and ejecting unit.

6. A card index file, comprising a cabinet open at the top, a plurality of tray holders slidably engaged in said cabinet body through said open top, each tray holder having a plate section extending transversely of said body, guide sections on the side edges of said plate section and a bottom wall on the lower end of said plate section, the upper end and the side opposite said plate section being open, retaining means detachably mounted on said cabinet for retaining said tray holders in assembled compartment forming relation therein, a plurality of card index trays one slidably mounted in each tray holder through the open upper end, and combined cushioning and ejector units, one detachably mounted on the bottom wall in each tray holder at the bottom of the compartment provided thereby, each unit including resiliently projected means for engaging the bottom of a card index tray and partially ejecting it out of said compartment, said means operating to cushion the downward movement of a card index tray in its compartment toward housed position therein arranged to have the weight of said tray over-balance said cushioning and ejecting means at the bottom of its movement into the compartment whereby said tray remains in housed position in said compartment ready for partial ejection therefrom by said means upon subsequent manual starting of its outward movement.

7. A card index file, comprising a cabinet body open at the top, a plurality of tray holders slidably engaged in said cabinet body through said open top, each tray holder having a plate section extending transversely of said body, guide sections on the side edges of said plate section and a bottom wall on the lower end of said plate section, the upper end and the side opposite said plate section being open, retaining means detachably mounted on said cabinet for retaining said tray holders in assembled compartment

forming relation therein, a plurality of card index trays one slidably mounted in each tray holder through the open upper end, and a plurality of cushioning and ejector units, one detachably mounted in each tray holder adjacent said bottom wall, each of said units including a toggle and resilient means normally operating said toggle toward broken position for engaging between said bottom wall and the lower end of a tray in said tray holder to partially eject said tray from said tray holder in removing the tray from its compartment, said tray being operable upon movement toward housed position to engage said toggle and move it toward straightened position against the bottom flange of said tray holder and over-balance the resilient means in housed position in said tray holder by its own weight for remaining in housed position in said cabinet ready for the next ejecting operation by said unit upon manual starting of the tray 20 outwardly from said tray holder.

8. A card index file, comprising a cabinet having a bottom, side and end walls and having an opening in the top, a series of tray holders mounted in said cabinet through said opening 25 in adjacent assembled compartment-forming relation with each compartment opening at the upper end through the opening in said top, positioning members mounted on each tray holder engaging the bottom of said cabinet in the assembled relation of said tray holders therein for holding said tray holders in fixed relation in said cabinet, a card index tray for each tray holder slidably mounted therein through the opening at the top, a plurality of cushioning and ejector units one mounted in the bottom of each tray holder between the lower end of the card index tray therein and said positioning member having parts resiliently projected upwardly in said tray holder to normally engage and partially eject the tray from said compartment in the withdrawal of said tray from said compartment, said tray operating said cushioning and ejecting means in movement into the compartment toward housed position against the normal operation of said cushioning and ejector unit for cushioning the movement of said tray into its tray holder into housed position, said cushioning and ejector unit being over-balanced by said tray as it reaches housed position in the tray holder wherein said tray is retained in housed position until it is manually started upon its next withdrawing operation, said positioning member transmitting the shock at the bottom of said tray holder from said cushioning and ejector units to said cabinet bottom.

9. A card index file, comprising a cabinet open at the upper end having bottom, side and end walls, a series of tray holders mounted in said cabinet through said open upper end and assembled in upwardly extending adjacent relation to provide a plurality of separate tray compartments in said cabinet opening at the upper end through said open top, a positioning member on each tray holder having parts thereon interengaged with complementary parts at the bottom of said cabinet for independently retaining each tray holder in fixed relation in said cabinet so that it may be independently inserted and removed through said open top, a plurality of card index trays, one slidably mounted in each tray holder, a pair of retainer bars detachably mounted on the upper end of said cabinet at each side of said tray holders, 75

extending transversely across the upper ends of all of said tray holders in said cabinet for retaining said tray holders in assembled relation in said cabinet and means on said retainer bars for cooperation with said card index trays to retain said trays connected to said cabinet in withdrawn relation.

10. A card index file, comprising a cabinet having bottom, side and end walls and open at the top, a series of tray holders extending transversely between the side walls of said cabinet, arranged in upstanding relation and assembled in adjacent relation between the opposite end walls to form a plurality of compartments opening at the upper end through said open top, a cover compartment at one end of said cabinet, a cover slideable into and out of said cover compartment for movement into a position over said open top to close the opening in the top of said cabinet and the open ends of said tray holders, retaining and guide means detachably mounted at the top on said cabinet engaging said tray holders and retaining them in fixed assembled compartment forming relation in said cabinet and having means thereon interengaged with complementary portions of said cover for guiding said cover during its movement between open position in said cover compartment and closed position on the top of said cabinet, and a plurality of card index trays one for each compartment slidably mounted therein for movement from housed position into and out of said compartment when said cover is in open position, said retaining and guide means having parts cooperating with complementary parts on said card index trays to prevent complete detachment of said trays from said cabinet when withdrawn from the compartment therein.

11. A card index file, comprising a cabinet body having a plurality of spaced parallel walls assembled to form a casing open at one side, a plurality of tray holders detachably engaged in said cabinet through said opening for cooperation in adjacent assembled relation to form a plurality of tray compartments, a pair of retaining and guide bars detachably mounted on opposite sides of the open end of said cabinet and extending transversely relative to said tray holders having a plurality of parts thereon each embracing the free ends of a pair of adjacent tray holders at the side edges and retaining said tray holders in adjacent assembled compartment-forming relation.

12. A card index file, comprising a cabinet body having a plurality of spaced parallel walls assembled to form a casing open at one side, a plurality of tray holders detachably engaged in said cabinet through said opening for cooperation in adjacent assembled relation to form a plurality of tray compartments, a pair of retaining and guide bars detachably mounted on opposite sides of the open end of said cabinet and extending transversely relative to said tray holders having parts thereon interengaged with the free ends of said tray holders at opposite side edges retaining said tray holders in adjacent assembled compartment-forming relation, a plurality of card index trays one slideable into and out of housed position in each compartment in said cabinet, said retainer bars being formed to provide parts having interengagement with complementary parts on said card index trays for retaining said card index trays against complete detachment from said cabinet in withdrawn position from its compartment.

13. A card index file, comprising a cabinet having a plurality of spaced parallel walls forming a casing open at one side, a plurality of tray holders inserted into said casing through said open side into independent adjacent assembled relation to form a plurality of tray compartments extending between opposite sides of said casing, a cover for the top of said cabinet, a cover compartment formed in said casing at one end, a pair of retaining and guide bars mounted at opposite sides on said cabinet and extending transversely across said tray holders for engagement therewith to retain said tray holders in assembled relation in said cabinet against detachment, said bars having guide projections thereon interengaged with complementary guide members on said cover for guiding said cover in its movement between open position housed in said cover compartment in said cabinet and closed position closing the opening in the side of said cabinet, said cover being formed to extend over said retainer bars in the closed position thereof on said cabinet to prevent access to said retainer bars and tray compartments.

14. A card index file, comprising a cabinet having a tray compartment formed therein opening through the top portion, a card index tray slidably housed in said compartment in upwardly extending relation, and combined cushioning and ejecting means mounted on the bottom of said compartment including a pair of links pivotally connected together, one link having an end opposite the connection with the other link pivotally secured to said cabinet at one side of the bottom of said compartment, the other link having the free end engaged with said cabinet at the bottom of said compartment for transverse movement across said compartment toward and from said pivot mounting for the first-mentioned of said links, means carried by an extension from the end of one of said links adjacent the pivotal connection of said links for engaging the end of said card index tray in the bottom portion of said compartment, and a ten-

sion spring connecting the ends of said links opposite said pivotal connection normally operable to move the free end of the second-mentioned link toward the pivot of the first-mentioned link to project said tray outwardly from said compartment and to cushion and arrest its inward movement therein.

15. A card index file, comprising a cabinet having a tray compartment formed therein opening through the top portion, a card index tray slidably housed in said compartment in upwardly extending relation, and combined cushioning and ejecting means mounted at the bottom of said compartment including a pair of links pivotally connected together and having the opposite end of one link pivotally connected to said cabinet in the bottom of said compartment and the opposite end of the other link movable transversely across the bottom end of said compartment in the pivotal movement of said links relative to one another for obtaining a movement of the pivotal connection of said links toward and from the front end of said compartment, resilient means normally actuating said links for moving the connected ends thereof toward the front of said compartment, and means carried at the pivotally connected ends of said links for engaging and normally projecting said tray outwardly from said compartment, said tray actuating said links and resilient means upon movement into said compartment to move the pivotal connection thereof toward the rear end of said compartment into a position slightly above the plane extending through the outer ends of said links whereby said links and resilient means cushion the inward movement of said tray into said compartment and said tray maintains the pivotal connection between said links adjacent the bottom of said compartment for maintaining said spring under tension for a subsequent ejecting operation of said tray thereby.

NIELS YDE ANDERSEN.
